UNITED STATES PATENT OFFICE.

JOHN D. HALL, OF PHILADELPHIA, PENNSYLVANIA.

CUFF-HOLDER.

SPECIFICATION forming part of Letters Patent No. 377,753, dated February 14, 1888.

Application filed May 21, 1887. Serial No. 238,976. (No model.)

To all whom it may concern:

Be it known that I, JOHN D. HALL, a citizen of the United States, residing at Philadelphia, in the county of Philadelphia and State of Pennsylvania, have invented certain new and useful 5 Improvements in Coat and Dress Sleeve Cuff Attachments; and I do declare the following to be a full, clear, and exact description of the invention, such as will enable others skilled in the art to which it appertains to make and use 10 the same, reference being had to the accompanying drawings, and to the letters and figures of reference marked thereon, which form a part of this specification.

15 The special object of my invention is to make a coat and dress sleeve cuff attachment which will enable a person to quickly and easily attach a cuff, cause the cuff to show the same margin, whether the arm be raised up or hanging down, and also to come off with the sleeve. The latter is a great convenience, especially to 20 business men, clerks, and working people who may wish to remove their cuffs when at business or work.

25 Figure 1 of the drawings is a perspective view of my invention applied; Fig. 2, an end elevation of the attachment, and Fig. 3 a perspective view of a modification of my attachment. Fig. 4 is a perspective view of a cuff- 30 fastener made of wire.

In the drawings, A represents my cuff attachment, which consists of two end curved and toothed jaws, a a, arms a' a', and ears a' a'. The latter lap each other and turn upon or 35 with a pivot, B, against the ends c c of a spring, C, coiled around the pivot.

To one of the arms a' is attached the tongue D, which carries a standard, d, slotted to receive the shank e of a button, E, said shank 40 having been turned through said slot and carried up to the under side of the button.

The modification shown in Fig. 3 is the same in principle as the device shown in Fig. 1; but I use a spring-clamp, F, instead of the button E, and make the jaws G G of plate- 45 springs, the latter facing each other. By my invention a lady's or gentleman's cuff may be attached to the lining of dress or coat sleeves rather than to the under-garments.

In using the device shown in the first figure 50 of the drawings, insert the button in the button-holes of a cuff; then slip on the cuff under the coat-sleeve, and fasten to the lining of the sleeve by opening the jaws by pressure with the finger and thumb on the arms a' a'; then with 55 another finger press the lining of the sleeve down between the jaws a a. After experimenting a few times it may be done quickly and with little or no trouble.

With the modification shown in Fig. 3 of 60 the drawings the attachment is held by clamp F to the cuff, while the jaws G G hold the lining.

When made of wire, as shown in Fig. 4 of 65 the drawings, the jaws a a, which grasp the sleeve-lining, are opened by pressing the arms d d of the tongue D together, and closed by their own spring-tension while the button is secured in the button-holes of the cuff.

What I claim as new, and desire to protect 70 by Letters Patent, is—

A cuff-holder having the jaws a a, arms a' a', pivot B in ears a' a', spring C, having ends c c, and plate D, carrying the button E, as 75 shown and described.

In testimony whereof I affix my signature in presence of two witnesses.

JOHN D. HALL.

Witnesses:

EDWARD E. PAXSON,
CHAS. S. KING.
